UNITED STATES PATENT OFFICE.

GEORGE W. HAYMAN, OF DUSHORE, PENNSYLVANIA.

FASTENING ATTACHMENT FOR BUCKLES.

SPECIFICATION forming part of Letters Patent No. 394,072, dated December 4, 1888.

Application filed June 7, 1888. Serial No. 276,295. (No model.)

To all whom it may concern:

Be it known that I, GEORGE W. HAYMAN, a citizen of the United States, residing at Dushore, in the county of Sullivan and State 5 of Pennsylvania, have invented certain new and useful Improvements in Fastening Attachments for Buckles and Like Articles; and I do declare the following to be a full, clear, and exact description of the invention, such 10 as will enable others skilled in the art to which it appertains to make and use the same, reference being had to the accompanying drawings, and to the letters and figures of reference marked thereon, which form a part 15 of this specification.

My invention relates more particularly to buckles, and has for its object to produce such an article with a fastening that will permit it to be easily and quickly applied 20 and detached without the necessity of stitching or sewing; and to such end the invention will be hereinafter particularly described and then claimed, reference being had to the accompanying drawings, forming a part 25 hereof.

Figure 1 is a perspective view showing a buckle having the spiral fastening. Fig. 2 is a perspective of a buckle with the screw-fastening.

30 In the drawings, the letter A designates a buckle having the fastening B applied thereto, and, as shown in Fig. 1, being in the preferred form of a spiral, although it may be in the form of a screw, as shown in Fig. 2. 35 The fastening is secured to the buckle in any suitable way, but preferably by bending the upper end of it downward, as shown at a, so as to straddle the cross-bar C of the buckle on one side of the tongue D, and then 40 upward, as shown at b, and again downward, as shown at c, on the other side of the cross-bar, and so as to lie upon the opposite side of the tongue to the first bend, and the portions of the fastening immediately below the cross- 45 bar are contracted, so as to confine the fastening to the buckle. By bending the fastening, as described, there are formed as a part of it two loops, one of which straddles or encircles the cross-bar and the other straddles or encircles the tongue, so that the fastening is not only secured to the cross-bar, but is also held to its position about the tongue and kept from sliding laterally, although the buckle-frame is free to turn where 55 the fastening B joins it, as is necessary and

apparent from an inspection of the drawings.

The buckle so constructed can be applied to any use to be made of it, and is attached readily by simply screwing it into place without the necessity of any sewing or stitching whatever. It is particularly well adapted to application to harness, and is of especial advantage for use in fastening horse-collars at their top, and in attaching sweat-bands to 65 collars, as well as to other uses which can be made of it.

I have described and illustrated what I consider to be the best method of securing the fastening to the buckle; but I do not 70 mean to restrict myself thereto, although such particular means or manner will be claimed.

I have shown both the spiral and threaded form of screw; and while the former is preferred, as it has advantages in this connection over the threaded form, still both forms 75 will be included in the term "screw."

Among the advantages of this form of buckle may be mentioned the ease and quick- 80 ness with which it can be applied and consequent saving of time and labor, the simplicity of its construction, and the durability in its use.

Having described my invention and set 85 forth its merits, what I claim is—

1. As an article of manufacture, a buckle for harness and the like provided with a pointed screw for its attachment, said screw having a loose connection with a part of the 90 buckle, substantially as and for the purposes herein set forth.

2. As an article of manufacture, a buckle provided with a spiral fastening, B, for its attachment, said fastening having a loose 95 connection with a part of the buckle, substantially as and for the purposes set forth.

3. The combination, with the buckle, of the spiral fastening B, formed with the two loops, one to lie across the cross-bar and the 100 other on opposite sides of the tongue, substantially as and for the purposes herein set forth.

In testimony whereof I affix my signature in presence of two witnesses.

GEORGE W. HAYMAN.

Witnesses:

RUSH J. THOMSON,
JOHN H. CRONIN.
